UNITED STATES PATENT OFFICE

MICHAEL SMETKO, OF CICERO, ILLINOIS, ASSIGNOR TO THE ART INSTITUTE OF CHICAGO,
OF CHICAGO, ILLINOIS, A CORPORATION OF ILLINOIS

DISPLAY CABINET

Application filed May 5, 1932. Serial No. 609,380.

These improvements relate to cabinets for holding articles for display.

It is customary in museums of art, natural history, etc., to display objects in cases formed with glass panels rising from a suitable base. Such objects are frequently of great and even incalculable value, but in any event they should be protected against handling by unauthorized persons, sometimes against cupidity, and at all times from the dirt and dust which would mar the display or injure the article. Accordingly the larger cases used for such purposes have ordinarily been formed with at least one of the large glass plates removable, as by the withdrawal of a number of screws around its margin, whereby access may be had to the interior for removing one exhibit and inserting another; and for this purpose from several to half a dozen workmen will be required, at considerable expense, loss of time, and not infrequent breakage of the glass panel being removed or replaced.

In connection with relatively small display cabinets for such purposes, and especially cabinets for objects comparatively low and which may rest upon the horizontal support constituting the top of the base, for example a table-top, it has been suggested to provide a rectangular glass cover having an open bottom resting on the base, with a rack secured to the cover at each corner thereof and extending vertically downward into the hollow legs of the table, with means such as shafts and gears operated by a crank for simultaneously raising and lowering the racks and thereby similarly moving the cover vertically, first to expose the top surface of the base beneath the lower edges of the cover, and then to return the cover to the top surface of the base. That device has proven advantageous in its limited field of relatively small articles to be displayed.

The objects of the present invention are to provide a cabinet whereby the articles displayed therein are given the desired safety and security, and whereby one may, with notable ease and celerity, and without the use of any workmen or loss of time, obtain access to the interior, especially in instances

where the items to be displayed are substantially high, or where a substantially high cabinet is desired for displaying a given group or collection of small objects, as on shelves one above the other, or where the articles may properly be secured to a back wall of the device or on special holding means within the device and extending upward a considerable distance. In the older form mentioned the observer ordinarily looks downward upon the articles. According to the present invention the observer may look downward upon the articles resting on top of the base, but the invention contemplates chiefly that he will look at the objects in a generally more horizontal direction, viewing the objects in side view rather than in top view. This elevational aspect of the objects displayed is usually the proper one, and the present invention therefore contemplates, as one of its advantages, this more favorable optical approach to the articles displayed. The invention contemplates also the quantity of such material that may properly be displayed in a single cabinet having the advantage of ready accessibility, such quantity being relatively large.

While cabinets in accordance with this invention may be made in any suitable size, the chief merit of the device will be found in cabinets of substantially great width and height. Thus in art museum practice they will ordinarily range from say five feet to ten feet in width, with a height of the display cover member extending from say four to eight feet above the base. For the display of tapestries and the like the horizontal depth of the display cover, from front to back, may be quite shallow, with the height and width of substantially great proportions suitable to the dimensions of the flat sheet-like fabric displayed. In such case instead of having a base substantially deep from front to back, otherwise necessary for stability, the base and its back may be secured firmly upon a vertical wall of the gallery.

In the accompanying drawings I have shown an embodiment of the invention in a form and construction which I now consider

most suitable and appropriate for art museum work and the like.

In these drawings Figure 1 is a perspective of the device with the cover member in closed 5 position;

Fig. 2 is a rear view of the device, with the back cover wall removed and various other parts omitted, this view being intended chiefly to show frame constructions;

10 Fig. 3 is a fragmentary sectional view on the line 3—3 of Fig. 5;

Fig. 4 is a medial vertical sectional view on the line 4—4 of Fig. 1 or 4—4 of Fig. 6, inner portions being broken away;

15 Fig. 5 is a view similar to Fig. 4 taken on the section line 5—5 of Fig. 1 or 5—5 of Fig. 6;

Fig. 6 is a fragmentary horizontal sectional view on the line 6—6 of Figs. 1 and 4;

20 Fig. 7 is an enlarged fragmentary sectional view of details, as on the line 7—7 of Fig. 4.

The base 10 is shown as a rectangular hollow body covered exteriorly with board material and having a front wall 11, side walls 25 12 and 13, and a rear wall 14 extending upward beyond the base, the horizontal area of the base being preferably a little larger than that of the vertical projection of the cover member 15, for the sake of stability. It may 30 be of any appropriate height, and its general proportions and construction may vary within wide limits.

The present device, in the preferred form 35 illustrated, contemplates a strong and rigid base having, preferably at its rear portion, a strong and rigid back member rigidly upstanding, and an open-bottom cover member mounted to move up and down on that back member, with means for raising and lowering 40 the cover member thereon. What I shall herein call the back member illustrated comprises a plurality of frame parts and other elements and is, as a whole, the upstanding part of what is a substantially L-shaped 45 frame structure, the base being the horizontal part thereof and the back member being the vertical part thereof.

The front and side walls 11, 12 and 13 of 50 the base 10, while providing ornamental finish and giving the base the character of a cabinet, contribute to the strength of the base and reinforce the framework within, the inner framework, however, being designed 55 chiefly to carry the strains. This inner framework comprises first a pair of stout wood pieces 16 at the bottom, to which is strongly secured board material 17 forming a partition closing the bottom of the hollow 60 base. Above this partition 17 there is a pair of upper and lower front frame members 18 and 19 (Fig. 4) strongly connected together by vertical end pieces 20. Upper and lower end frame members 21 and 22 extend rearwardly and are supported by the rear up-

rights 23 and 24 connected together by a cross member 25.

As thus far described the base portion comprises a rigid frame secured to the platform 17 and the bottom wood pieces 16. The 70 downwardly-extending leg portions 26 and 27 of the back wall 28 (see Fig. 2) are secured to the rear uprights 23 and 24. A top platform 29 is secured to frame members 18, 21 and 25 and provides a horizontal support for objects to be displayed. Between the front wall 11 and the frame member 18 (see Fig. 4) a space 30 is provided to receive the lower frame element 15a of the cover member 15; and between the respective side walls 12, 13 and the side frame members 21 (see Fig. 3) a space 21a is provided to receive the lower edges respectively of the cover side-wall elements 15b. The lower edge of the cover member is thus sealed at the front and sides by entering the spaces 30 and 21a respectively.

The cover member 15 is slidably mounted on the back wall 28, at the side edges of the back wall, by means of a groove 31 in back 90 wall 28 (Fig. 6) and a tongue 32 in the rear vertical side-wall element 33 of the cover 95 15. These side-wall elements 33 are also provided with a rearwardly-extending tongue 34 extending vertically the full length of element 33 into a groove 35 in the uprights 36 (see also Fig. 1) secured to the base 10. These uprights 36 are connected at their top ends by means of a cross member 37 (Figs. 1, 2, 4 and 5) provided with an upwardly-facing groove 38 into which a downwardly-extending tongue 39 of the top frame element 40 of the cover 15 extends. These tongue-and-groove 100 formations seal the interior of the cover member when the cover is in its lower or closed position as shown by full lines in Fig. 1, and the lateral tongue-and-groove elements also serve to some extent in guiding the cover member in its up and down movements.

At its lower side edges the cover member 15 is provided with downwardly-extending side walls 41 which pass freely into the space 21a (Fig. 3). Fig. 5 shows that these depending cover side walls 41 (they are the same at both sides) are quite long and extend to the bottom partition 17 at their rear portions while their front portions extend to the front of the cover member. They are secured strongly and rigidly to the cabinet part of the cover member at the front cross member 15a (Figs. 4 and 5) and themselves form the lower side frame elements 15b of the cover member. What we see at 15b in Fig. 1 is therefore the top edge portion of one of these depending side walls 41.

The rectangular cover member 15 comprises a front wall 15c, side walls 15d, and a top wall 15e, the front and side walls being preferably of transparent glass, while the 130

top wall is preferably of glass "frosted" to diffuse the top light. The back of the cover member is open, as is also its bottom, meaning that the cover member does not have either a back wall or a bottom wall. I have pointed out how the rear vertical edges of the cover member are guided for up and down movements.

The four glass panels of the cover member are held together in the form of a rigid case or housing by moulding framework at their meeting edges in the usual way. At the rear side edge portions and at the top of the cover member this framework takes the form of relatively wide strips of board material serving to cover some of the parts of the device rearward of the display portion of the cabinet and also to provide strong frame elements carrying the weight of the cover when in raised position.

Fig. 2 shows a steel or iron frame comprising a pair of oppositely disposed vertical T-rails 43, and another transverse angle-iron 45, both rigidly connected to the T-rails 43. This iron frame is rigidly connected at the top by screws 46 to back wall 28 and by angle-iron cleats 47 to the rigid rear top frame element 37. At their lower end the T-rails 43 are rigidly secured by angle-iron cleats 48 to the laterally- and downwardly-extending parts 26 and 27 of the back wall 28, and are thus rigidly connected also to the main frame structure of the base 10. The back member as a whole thus comprises a back wall 28, a reinforcing iron frame and an outer frame structure comprising the board-material elements 36 and 37. All of these several back member parts are rigidly secured together and to the base.

Since the cover member will usually be quite heavy and is carried at its rear edge portions only, the cover member must be carried strongly and for free and easy movements. To this end the cover member is mounted on the vertical T-rails 43. Fig. 6 shows a pair of rollers 50 straddling and bearing on web 43a of T-rail 43. Fig. 5 shows these rollers 50 as carried by a piece of strap iron 51 rigidly secured by screws at the upper portion of the downwardly-extending side walls 41 of the cover member. Note from Fig. 6 that a bar 52 is welded at 52a to strap iron piece 51, and this bar 52 extends to and is similarly secured to the corresponding strap iron piece 51 at the opposite side of the device.

Next note that at the bottom of the side members 41 there is another pair of rollers 54 carried by a strap iron piece 55 rigidly secured to side member 41, these rollers 54 also engaging the web 43a. Strap-iron bracket 55 extends rearward of rollers 54 and turns into the transverse bar 56 extending across the device and into the opposite piece 55 secured to the opposite wall 41. In other words, the strap iron member marked

55 and 56 in Figs. 5 and 6 is a single U-shaped piece, the construction at both sides being the same. We thus see that the cover member is mounted on the iron frame by four pairs of rollers, the opposite upper pairs 70 being spaced a considerable distance from the opposite lower pairs respectively.

Means for elevating and lowering the cover member 15 are illustrated for example, and as I employ the same in practice, as including, first, a vertical screw shaft 60 mounted for rotation in a bearing 61 at its lower end (Fig. 4), which bearing is carried by transverse angle-irons 45 (Fig. 2), and in a bearing 62 at the top carried by angle-iron 44. On shaft 60 is a nut member 63 which is secured on one side to the horizontal bar 52. A bracing iron 64 is secured to the nut member and to bar 52 (see Figs. 4 and 6). Vertical movement of the nut member is therefore communicated through bars 52 and 64 to the strap-iron pieces 51 carrying the rollers 50 respectively.

Fig. 2 shows a vertical bar 66 secured to transverse bars 44 and 45, its lower end extending to a place close to the bottom of the device.

Fig. 7 shows that cross bar 56 has a pair of gibbs 67 engaging for sliding movement vertical bar 66. This vertical bar 66 constitutes 95 a reinforcement of the frame and provides, with the gibbs 67 and associated parts means for guiding the cover member movements, especially against any tendency of the cover member to sag at either side. Gibs 67 therefore fit the bar 66 snugly, yet for sliding movements.

Further means for raising and lowering the cover member are shown as a bevel pinion 70 on screw shaft 60 and meshing with bevel pinion 71 on crank shaft 72 mounted in bearings 73 on an angle-iron support 74 secured at its rear end to angle iron 45 of the iron frame and at its front end to an extension 18a of front frame part 18 (Fig. 4). The front end of shaft 72 is squared at 75 to receive a socketed crank 76 shown in dotted lines in Fig. 1, and which may extend through a hole 77 in front wall 11 of the base. The numeral 78 (Fig. 1) indicates a 110 removable key-operated lock which normally fills the hole 77 to prevent unauthorized use of the crank 76.

Turning the crank rotates the screw shaft and raises and lowers the cover member. Fig. 1 shows by dotted lines that the cover member may be raised to such an extent that its lower edge comes almost to the top of the back wall 28, thus exposing substantially the entire area of that back wall and making every part of the exhibition space accessible.

In front of the back wall 28 I provide a substantially flat background piece 80, of board material, and secured for ready removability to the back wall, as by screws 81 130

(Figs. 4 and 5). This diaphragm 80 may receive the articles to be displayed or it may carry shelves as 82, 83 on which articles may be placed. The back wall 28 similarly may receive the articles or carry the shelves. Other articles may be placed on top wall 29 of the base. In displaying high objects, for example a statue, the shelves would be omitted. I provide the wall 80 chiefly as means for the convenient application of ornamental fabric for background purposes which may be placed over the front of board or plate 80 and turned around its edges, giving the background a finished appearance. Rear wall 14 is held by screws 90 (Fig. 4) and is readily removable for access to the mechanisms in front of it. It will be noted that the device may be placed closely against a wall of the exhibition room, or that two of the devices may be arranged back to back.

I have shown the back member as comprising various parts assembled into what as a whole is a substantially flat structure uprising from the base. Where a plate-like back member is specified in appended claims either back wall 28 or 80 may be considered to be that element. While the tongue-and-groove joints in the framework illustrated are not designed to carry severe strains, but are rather for sealing, it is clear that the chief or only sliding connection could be of that kind, especially if the device were made with a metal frame. Various departures may be made in structural respects within the invention, and I contemplate as being included in these improvements all such variations, changes and departures from what is thus specifically illustrated and described as fall within the scope of the appended claims.

4. I claim:

1. A display cabinet comprising a base adapted to rest upon the floor and having a substantially flat back member rigid therewith and upstanding therefrom, said back member being substantially wide and high, a unitary cover member having front and side walls, at least the front wall being transparent, the cover member having also a top wall, the bottom of the cover member being open, the rear edge portions of the cover member interfitting for vertical sliding movements with said back member, lower edge portions of the cover member interfitting with the base, and the rear edge portion of the top of the cover member interfitting with the back member, the cover member thus providing a closed compartment above the base and in front of the back member and being movable vertically on the back member, and mechanical means carried by the base for raising the cover member by a sliding movement on the back member to such a substantially great height as to provide access to substantially the entire area of the back member.

2. The cabinet of claim 1 hereof in which the base is in the form of a substantially rectangular casing and said cover member is substantially rectangular and of approximately the horizontal width and depth of the base, the back member being of substantially the width and height of the cover member, and said mechanical means being adapted to elevate the cover member whereby its lower edge in front comes substantially close to the horizontal plane of the top of the back member.

3. The cabinet of claim 1 hereof in which said back member is at the rear of the device and there is a plate-like background member secured for ready removability to and in front of said back member to serve as a background for the articles to be displayed.

4. In a device of the character described, a base having a top on which articles may be displayed, a plate-like back member rigid with and upstanding from the base, a cover member having at least one transparent wall and being open at its bottom and at its rear side, said cover member resting on the base and being mounted to slide upward and downward relatively to the back member, and mechanical means operable by hand for raising and lowering the cover member relatively to the back member.

5. The device of claim 4 hereof in which said means for raising and lowering the cover include a rotatable vertically-disposed screw shaft, a nut member on said shaft, and means connecting the nut member with said cover member whereby when the nut member moves up and down the cover member moves likewise, with means for rotating said screw shaft.

6. A display cabinet comprising a base having a rigid back upwardly extending therefrom, a unitary cover member having an open back and an open bottom and interfitting for vertical movements on said back, said cover member interfitting with said base to close the cover member at the bottom thereof, and mechanical means for raising the cover member by a sliding movement on the back.

7. A display cabinet comprising a base having a flat back upwardly extending rigidly therefrom, a cover member having a top wall and front and side walls, the cover member being mounted for vertical movements on the back, the cover member interfitting with the base to close the cover member at the bottom, a vertically-disposed screw shaft extending substantially the height of the back, nut means carried by the cover member and engaging the screw shaft, and means including a crank for manually turning the screw shaft for moving the cover up and down.

8. In a device of the character described, a base having a top on which articles may be

displayed, a back including a pair of vertical guides rigid with and uprising from the base, a cover member having at least one transparent wall and being open at its bottom, 5 said cover member normally resting on the base and being mounted to move upward and downward on said guides, and means operable by hand for raising and lowering the cover member on and relative to the back.

10 9. The cabinet of claim 8 hereof in which there are means carried by relatively fixed parts of the device for supporting articles within the cover member and above the base.

15 10. The cabinet of claim 8 hereof in which there is a flat background member rigidly upstanding within the cabinet and constituting a rear wall for the cover member when the cover member is in closed position.

20 11. A display cabinet comprising a base having an upstanding back member, an open-bottom cover member slidably mounted on the back member, the back member including vertical guiding means for the cover, and means for raising and lowering the cover 25 member on and relatively to the back member.

25 12. A display cabinet comprising a base having an upstanding back member including an upstanding rear wall and associated 30 means forming a compartment, a vertical guiding means and a vertical screw shaft in said compartment, a nut threaded on said screw shaft, a cover member having an open bottom mounted to move up and down on said 35 guiding means, means connecting said cover with said nut, and manually operated means for turning the screw shaft to raise and lower said nut and thereby raise and lower said cover.
